UNITED STATES PATENT OFFICE.

NATHANIEL H. TALBOT, OF NORTH EASTON, MASSACHUSETTS.

DESIGN FOR SPIDER-GRATE.

Specification forming part of Design No. 5,144, dated July 25, 1871.

To all whom it may concern:

Be it known that I, NATHANIEL H. TALBOT, of North Easton, of the county of Bristol, of the State of Massachusetts, have invented or produced a new and useful Design for a Spider-Grate; and do hereby declare the same to be fully described in the following specification and represented in the accompanying drawing, of which—

Figure 1 is a top view, Fig. 2 a bottom view, and Fig. 3 an edge elevation of such grate.

It is composed of a flat circular annulus, *a*, a series of parallel bars, *b b*, and two external projections, *c c*, all being formed and arranged as represented. Each of the bars, at its opposite extremities, joins with the ring and projects be-

low it, and even or in the same plane with the projections *c c*, which also extend from the ring. The portions *c c* and the projecting parts of the bars, extending, as they do, beyond the lower face of the ring, serve to support the grate on the bottom of a spider or frying-pan and to hold it raised off, so that the heat and fat may freely circulate underneath the ring and between the bars of the grate.

I claim—

The design for spider-grate, as represented and hereinbefore described.

NATHANIEL H. TALBOT.
